INSULATOR

Frank J. Stevens, Victor, N. Y., assignor to
Locke Insulator Corporation, Baltimore, Md.,
a corporation of Maryland

No Drawing. Application December 7, 1925
Serial No. 73,890

9 Claims. (Cl. 173—318)

The invention relates to insulators of that type having a hole therein for the reception of a pin.

The principal object of the invention, generally stated, is to provide a novel method of forming pin receiving holes in insulators.

It is well known that the ordinary method at present employed is to form the insulator with a threaded hole by means of a die or dies which operate on the insulator, while it is still in a "green" or plastic condition, to form a threaded hole into which the pin may be subsequently screwed. A great difficulty has been that upon firing the insulators the resultant shrinkage is not necessarily uniform throughout a single piece or in different pieces and as a consequence the holes are frequently of different diameters in different pieces and out of true in the individual piece. In addition to being out of round, the taper of the hole, after firing, is frequently too great or too little for the proper reception of the pin.

To overcome the above mentioned difficulties expedients have been resorted to but with indifferent success as for instance it has been contemplated to cement a metal thimble of standard dimensions in a hole formed at the center of the insulator body or shell, but the use of such a thimble is almost prohibitive on account of the cost thereof and the cost of the labor involved. It has also been attempted to produce the desired result by casting a lead thimble in a sanded pin hole, the casting being done about a mold which must of course be subsequently withdrawn. This latter mentioned method is impracticable for the reason that the lead comes in contact with the porcelain while in a molten condition and necessarily at such a high temperature that cracking of the porcelain of the insulator frequently results.

The above facts have resulted in the present invention which has for its more specific object the provision of a method of forming a pin hole by means of a suitable cement cast about a proper mold inserted within an ordinary hole formed in the insulator body while the latter is in a plastic condition, the casting of the pin hole by means of the cement being accomplished subsequent to firing, it being, therefore, unnecessary to subject the cement to a high temperature or other condition which might cause impairment of the material itself or distortion or change in size of the pin hole.

In the actual carrying out of the invention the insulator is formed with an ordinary hole while

in a plastic condition and is of course fired in the usual manner. The hole is preferably, though not necessarily, sanded. Even though the shrinkage during firing should happen to be uneven, any lack of trueness in the hole would be of no consequence inasmuch as the hole is of a considerably larger diameter than the contemplated diameter of the pin hole to be formed. A mold of suitable construction and mounting and operable by any desired means, but of course conforming to the particular type of pin to be used with the insulator, is then placed centrally within the hole and a proper cement is poured or otherwise placed within the hole about the mold and permitted to set, after which the mold is withdrawn, leaving a threaded hole of true form and proper pitch capable of receiving a standard pin.

Obviously, if the hole in the insulator body be sanded or otherwise roughened the holding action of the cement will be increased. In lieu of sanding or roughening, it is conceivable that the initial hole might be undercut, if preferred, or otherwise formed to insure adequate retaining means for the cement in which the pin hole is formed. In actual practice I have found that aluminate cement is highly satisfactory for the purpose. This particular variety of cement is put out by the Atlas Lumnite Cement Company under the trade name of "Lumnite" which was registered in the U. S. Patent Office as a trademark, the registrations being Nos. 192,958 and 261,704. Analysis of this cement discloses its ingredients to be as follows:

	Lumnite	Per cent
SiO ₂		90
Fe ₂ O ₃		5
Al ₂ O ₃		15
CaO		39
MgO		38
SO ₃		1
Loss		95

The advantage of using this particular substance is that it possesses certain characteristics as to smoothness, homogeneity and hardness as will render a pin hole therein as satisfactory as one in a thimble or bushing. Furthermore, the formation of a pin hole in this manner causes no strain whatsoever on the porcelain of the insulator and there is naturally no injury thereto.

While I have described the detailed operations involved in the method it should be understood that this is for illustrative purposes only as I reserve the right to make any such changes in the

- detailed steps involved and the particular material employed as do not constitute any departure from the spirit of the invention or the scope of the claims hereunto appended.
- 5 Having thus described the invention, I claim:
1. An insulator comprising a porcelain body having a hole therein, and a lining for the hole formed of aluminate cementitious material united to the wall of the hole and having an opening corresponding to a pin.
  - 10 2. An insulator comprising a dielectric body having a cavity therein, and a filling within the cavity formed of aluminate cementitious material, said filling having a hole therein adapted to receive a pin.
  - 15 3. An insulator having a hole therein lined with aluminate cement.
  - 20 4. An insulator comprising a dielectric body having a cavity therein, a pin to be mounted within the cavity, and a mass of aluminate cement filling the space between the wall of the cavity and the pin.

5. The insulator comprising a plurality of members held together by a cementitious mass of aluminate cement.
6. The insulator comprising at least one insulating component and a cementitious mass of 80 aluminate cement associated therewith.
7. The insulator comprising members held in a predetermined relationship by a layer of material, said material comprising aluminate cement.
8. An insulator comprising a dielectric body, a metallic member, and a mass of aluminate cement securing the metallic member to the dielectric body.
9. An insulator comprising a dielectric body, a metallic member, and means comprising aluminate cement for securing the body and metallic member to each other in predetermined spaced relation.
